NORMAN B. CLABAUGH, OF FREDERICK, MARYLAND.

Letters Patent No. 66,219, dated July 2, 1867.

IMPROVEMENT IN CHURNS.

The Schedule referred to in these Letters Patent and making part of the same.

TO ALL WHOM IT MAY CONCERN:

Be it known that I, NORMAN B. CLABAUGH, of Frederick, in the county of Frederick, and State of Maryland, have invented a new and improved Churn; and I do hereby declare that the following is a full, clear, and exact description thereof, reference being had to the accompanying drawings, making a part of this specification, in which—

Figure 1 is a longitudinal section taken in a vertical plane through the improved churn.

Figure 2 is a transverse section through the churn, taken in the vertical plane indicated by red lines $z-z$ in fig. 1.

Similar letters of reference indicate corresponding parts in the two figures.

The nature of my invention consists in a rotary churn-dash, which is adapted either for a box or barrel churn, and which is composed of open radial wings having a great number of pins or breakers applied to them in such manner as to rapidly break up the butter globules and agitate the cream to the best advantage; said wings or dashers being so constructed and applied to dash-heads as to leave a space in the centre thereof for receiving and allowing of the conglomeration of the butter kernels as the wings gather the butter, as will be hereinafter described.

To enable others skilled in the art to understand my invention, I will describe its construction and operation.

In the accompanying drawings, A represents a churn-box of a rectangular form, and B is the cover of this box, which is provided with a glass window, a , and also with a pipe, b . The window allows of the inspection of the contents of the churn during the operation of churning, and the pipe b allows air to pass freely into and out of the churn-box during the operation of churning, without allowing cream to escape therefrom. Within this churn-box are the dashers C C, which are secured to heads, D D', that have their bearings in the ends of said box, as shown in fig. 1. One head, D, is kept in place and sustained by a thumb-screw, e , upon removing which the dashers can be taken out of the box. The other head, D', has a plate, e' , secured to it, in which is a square socket for receiving the square inner end of a short shaft, E, upon the outer end of which a pinion spur-wheel, E', is keyed. This wheel E' engages with and is driven by a large spur-wheel, F, which is provided with a crank-handle, G, and which is applied upon a short shaft, f , that is secured fast upon the end of the churn-box, as shown in fig. 1. The interior enlargement, g , upon the shaft E, and the flanged collar, g' , prevent the escape of cream from the box at this point. The heads D D' are each made of two pieces of the same length, crossed and halved together, as shown in fig. 2, thus forming radial arms for receiving and having secured to them the longitudinal bars which form the dashers C C. The bars which constitute the open dashers are secured to their respective arms in lines parallel to each other at proper distances apart, and to the intermediate bars h , short pins, $p p$, are applied, by inserting them through holes which are made through these bars h in a direction toward the axis of motion of the dashers, as shown in figs. 1 and 2. These pins p are arranged pretty close together, so as to present a great number of beating and breaking points or surfaces to the cream in passing through it, and they are galvanized for the purpose of preventing them from rusting and discoloring the butter. They may be made square, prismatic, or cylindrical, and their ends may be made to touch the parallel bars on each side of the bar h , or spaces may be left at these points, as may be found desirable. It will be seen by reference to the drawings that there is no shaft passing through the dashers between the two heads D D', and that I leave a space between these heads and the dashers. The object of this space is to allow the butter to be gathered therein by giving the dashers an oscillating movement after the butter has "come," so that it can be readily removed from the churn.

Having described my invention, what I claim as new, and desire to secure by Letters Patent, is—

The construction of a rotary churn-dash of longitudinal parallel bars or wings, C C h , applied to heads D D', and provided with pins $p p$, applied substantially as and for the purposes described.
